(74) Attorney, Agent, or Firm:—James B Robinson

(21) Appl. No.: **29/350,027**

(57) CLAIM

(22) Filed: **Nov. 10, 2009**

I claim the ornamental design for a locked valve body with X,
as shown and described.

(51) LOC (9) Cl. **23-01**

DESCRIPTION

(52) U.S. Cl. **D23/233**

The sole view is a perspective view of the locked valve body
with X, showing my new design.
